F. LAPORTE

PURSE RETAINER

Filed Nov. 28, 1924

FIG. 2

FIG. 1

INVENTOR.

BY FRANK LAPORTE.

Harry J. Schwoedt
ATTORNEYS.

UNITED STATES PATENT OFFICE.

FRANK LAPORTE, OF OAKLAND, CALIFORNIA, ASSIGNOR OF ONE-HALF TO MAX JEFFRIES, OF OAKLAND, CALIFORNIA.

PURSE RETAINER.

Application filed November 28, 1924. Serial No. 752,692.

To all whom it may concern:

Be it known that FRANK LAPORTE, a subject of Belgium, residing at Oakland, in the county of Alameda and State of California, has invented certain new and useful Improvements in Purse Retainers, of which the following is a specification.

My invention is an improved design of purse retainer and may be applicable to wallets, pocket jewel cases or the like which it is desired to fasten in a pocket so that the article will not be accidentally lost or stolen. My invention is in the retaining mechanism and its mounting in various articles will be readily suggested. With my devise it is not necessary to have special fittings in a pocket or the receptacle in which the purse or jewel case is carried. My retainer is mounted or installed in a case for carrying valuables and has a number of bolts or lock bars which may be forced outward from the edge and grip the lining of a pocket.

The retaining mechanism will be placed in the case or purse, preferably, between the outside cover and the lining and does not materially interfere with the carrying capacity of the purse. In the broad aspect of my invention bolts or lock bars are actuated to slide in and out of the case and in their outward position engage the lining of a pocket or other receptacle. These bolts are, preferably, actuated by springs so that a constant pressure is exercised against the lining.

In the specific form of my invention illustrated I have a light rectangular frame, a pair of bell cranks pivoted to opposite side edges on the inside, with the bolts or locking bars carried by the ends of the bell cranks. Each bell crank has a slotted tongue through which a pin on an operating rod extends. This rod has springs connected thereto normally tensioned to force the bolts into locking position. A latching device, at the top of the case, holds the rod elevated and the bolts retracted.

My invention will be more readily understood from the following specification and drawings in which:—

Figure 1 is a side elevation of my purse retainer with the bolts or locking bars in position to engage a pocket or other receptacle. The case is shown in section.

Figure 2 is a side elevation of my purse retainer with the bolts or locking bars in retracted position, so that the purse may be

withdrawn from a pocket or other receptacle.

In the drawings 1 represents a light metal frame, preferably, rectangular, having sides 2 and 3, bottom 4 and top 5. Lugs 6 and 7 are rigidly secured to the sides and are split to form pivotal mountings 8 and 9 for the bell cranks 10 and 11. The bell crank 10 has lower arms 12, upper arm 13 and tongue 14; and the bell crank 11 has similar elements as lower arm 15, upper arm 16 and tongue 17.

The lower locking bolts 18 and 19 are pivotally connected to the arms 12 and 15 respectively by the pintles 20 and 21; and have sliding supports in the apertures 22 and 23 in the sides 2 and 3 respectively of the frame 1. The upper locking bolts 24 and 25 are longer than the lower bolts and are pivoted to opposite bell cranks as the bolt 24 is pivoted to the bell crank arm 16 by the pintle 26 and the bolt 25 is pivoted to the bell crank arm 13 by the pintle 27. The bolts 24 and 25 have sliding supports in the apertures 28 and 29 in the sides 2 and 3 respectively of the frame 1.

The tongues 14 and 17 of the bell cranks have slots 30 and 31 respectively, through which slots passes a pin 32 rigidly attached to an operating rod 33. A spring 34 is constantly tensioned between the lower end 35 of the rod 33 and a hook 36 attached to the bottom 4 of the frame 1. By this mechanism there is a normal force to actuate the bell cranks to the position shown in Figure 1 and thrust the locking bolts into operative position.

A latching device is provided by mounting the upper end 37 of the rod 33 in a slideable sleeve 38, which has a longitudinal slot 39 through which is extended the dog 40 on the end of the rod 33. The sleeve 38 passes through an aperture 41 in the top 5 of the frame 1 and has a collar 42 limiting its downward movement, which is caused by a spring 43 tensioned between a hook 44 on the sleeve 38 and a hook 45 attached to the bottom 4 of the frame 1. Any finger grip such as the ring 46 may be used to lift the sleeve 38.

A trigger device to hold the rod 33 in its upper position and the locking bolts retracted is constructed as follows:—A bracket 47, having two lugs 48 and 49 is riveted or otherwise fastened to the top 5 of

the frame 1. The lug 48 is shown abutting the doubled part 50 of the top 5. Thus doubling and riveting the top 5 gives it added strength. A trigger 51 is slidably mounted in apertures 52 and 53 in the lugs 48 and 49 respectively. The trigger, preferably is of lesser diameter at part of its length and has a spring 54 under compression between the shoulder 55 of the trigger and the lug 49, so that the trigger is normally actuated to engage and retain the dog 40 on the rod 33. A stud 56 is fixed to the end 57 of the trigger and slides through a slot 58 in the top 5 of the frame 1 and has a finger grip 59 outside of the frame and case 60 of the purse.

The locking bolts have buttons or other suitable tips 61 to contact with the pocket or receptacle in which the purse is carried and are attached to the bolts after they are thrust through apertures in the edges of the case 60.

The manner of operation of my purse retainer is as follows:—The mechanism when inserted in a purse has the collar 42, ring 46 and finger grip 59 of the trigger exposed at the top of the purse. The ring is pulled upward, elevating the sleeve 38 so that the lower end of the slot 39 therein lifts the rod 33 by means of the dog 40. When the dog engages the trigger 51 the rod 33 is held elevated, as shown in Figure 2, and the locking bolts 18, 19, 24 and 25 are retracted. The purse may now be readily withdrawn from the pocket or receptacle. When the purse is inserted in a pocket it is only necessary to move the finger grip 59 which actuates the trigger to release the dog 40 when the spring 34 will pull the rod 33 down and thrust the buttons 61 into contact with the pocket.

My retainer may be considerably modified to suit various designs of purses or the like without departing from the spirit of my invention.

Having described my invention what I claim is:—

1. A purse retainer comprising in combination a purse, oppositely positioned rectilinearly slidable bolts operatively connected therewith adapted to engage a pocket and mechanism in the purse to actuate said bolts.

2. A purse retainer comprising in combination a purse, oppositely positioned rectilinearly slidable bolts extendable therefrom adapted to engage a pocket and a spring actuated mechanism in the purse to extend said bolts.

3. A purse retainer comprising in combination a purse, a plurality of pairs of locking bolts slidable in substantially a rectilinear line in and out of the purse and a spring actuated mechanism in the purse to thrust the bolts outward.

4. A purse retainer comprising in combi-

nation a purse, a plurality of pairs of locking bolts slidable in substantially a rectilinear line in and out of the purse, a spring actuated mechanism in the purse to thrust the bolts outward and means to retract the bolts, said pairs of bolts being inter-connected to operate simultaneously.

5. A purse retainer as claimed in claim 4 having in addition a device in the purse to retain the bolts retracted.

6. A purse retainer comprising in combination a purse, a frame for the retainer in the purse, rectilinearly sliding locking bolts extending through the frame, a spring normally tensioned to extend the bolts secured to the frame, rectilinearly sliding means extending outside the frame to counteract the spring and retract the bolts.

7. A purse retainer as claimed in claim 6 having a latch secured to the frame to retain the bolts retracted.

8. A retainer for a purse comprising a frame, rectilinearly sliding locking bolts slidable through the frame, bell crank levers actuating the bolts, a rod operatively connected to the levers and means to operate the rod to slide the bolts.

9. A retainer as claimed in claim 8 in which the means to operate the rod to slide the bolts out comprises a spring tensioned between the rod and the frame.

10. A retainer as claimed in claim 8 having in addition a sleeve slidable on the rod engaging a dog thereon to retract the bolts.

11. A retainer as claimed in claim 8 having in addition a sleeve slidable on the rod engaging a dog thereon to retract the bolts and a trigger connected to the frame to retain the bolts retracted.

12. A retainer for a purse comprising a frame, bell crank levers pivoted to the sides of the frame, locking bars slidable through the frame pivotally connected to the arms of the levers, a rod operatively connected to the bell crank levers, a spring tensioned between the rod and the frame, a sleeve slidable on the rod having a slot, a dog on the rod projecting through the slot and a trigger connected to the frame to engage the dog.

13. A retainer as claimed in claim 12 having an extension of the sleeve outside the frame to slide the sleeve.

14. A retainer as claimed in claim 12 having a trigger release device operable from outside the frame.

15. A retainer as claimed in claim 12 having an extension of the sleeve outside the frame to slide the sleeve and a trigger release device operable from outside the frame.

16. A retainer for a purse comprising a frame, bell crank levers having a plurality of arms pivoted to the sides of the frame, locking bars slidable through the frame pivotally connected to the arms, a sleeve having a slot slidable through the frame, a rod

in the sleeve having a dog projecting through the slot, a loose connection between the rod and an arm of opposite bell crank levers, a spring tensioned between the rod and the frame, a spring tensioned between the sleeve and the frame and a trigger secured to the frame to engage the said dog.

17. A retainer as claimed in claim 16 having an extension of the sleeve outside the frame to slide the sleeve.

18. A retainer as claimed in claim 16 having a trigger release device operable from outside the frame.

19. A retainer as claimed in claim 16 having an extension of the sleeve outside the frame to slide the sleeve and a trigger release device operable from outside the frame.

In testimony whereof I affix my signature.

FRANK LAPORTE.
